UNITED STATES PATENT OFFICE.

JAMES H. CRAIG, OF MARION, INDIANA, ASSIGNOR OF SEVEN-SIXTEENTHS
TO V. R. BARLEY, OF SAME PLACE.

BAG-HOLDER.

SPECIFICATION forming part of Letters Patent No. 471,466, dated March 22, 1892.

Application filed June 20, 1891. Serial No. 396,924. (No model.)

To all whom it may concern:

Be it known that I, JAMES H. CRAIG, a citizen of the United States, residing at Marion, in the county of Grant and State of Indiana, 5 have invented certain new and useful Improvements in Bag-Holders; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to certain new and 15 useful improvements in bag-holders; and it has for its object to provide a simple and cheaply-constructed device of the character named which may be readily adjusted, so as to adapt it for use in connection with bags of 20 different sizes. The bag to be held open while being filled may be quickly and readily secured to the holder, will be securely held, and may be readily detached.

The device is particularly adapted for use 25 in connection with mail-bags.

To these ends and to such others as the invention may pertain the same consists in the peculiar construction and in the novel combination, arrangement, and adaptation of parts, 30 all as more fully hereinafter described, shown in the accompanying drawings, and then specifically defined in the appended claim.

The invention is clearly illustrated in the accompanying drawings, which, with the letters of reference marked thereon, form a part 35 of this specification, like letters indicating like parts throughout the several views, and in which drawings—

Figure 1 is a top plan view of a bag-holder 40 embodying my improvements. Fig. 2 is a bottom plan view of the same.

Reference now being had to the details of the drawings by letters of reference, A designates a rectangular frame, which may be constructed of either wood or metal.

B' are lugs or arms, which depend from the front and rear edges, respectively, of the rear timber B of the said frame and are designed 45 to embrace a strip attached to the edge of a

table or other support to which it may be proposed to attach the bag-holder when in use. 50

C and C' are curved arms, which form the supports for the bag. The arm C, it will be observed, is pivoted upon a fixed pivot D upon the front timber E of the frame A, and 55 at a point slightly in advance of the pivot D the said arm is provided with a pin or point F, which extends upward and is inclined slightly toward the rear from the upper face of the arm. The arm C' is in all respects 60 similar to the arm C just described, excepting that instead of being pivoted upon a fixed pivot it is pivoted upon an upwardly-extended pivot or rod H, which is passed through a slot H' near the opposite end of the timber E. 65 At the lower end of the rod H a set or thumb nut H² is provided, whereby the said rod may be secured at any desired point within the slot H', as will be readily understood. The rear ends of the arms C and C' are connected 70 by means of a spiral spring I.

The operation of the device is simple and readily understood. The frame A is secured to any suitable support by means of the downwardly-extending lugs B', which depend from 75 the front and rear edges of the rear timber B of the frame A. The arm C' is moved so as to adapt the arms to the size of the bag to be held, and is secured in its adjusted position by tightening the thumb-nut H². The mouth 80 of the bag is passed over the arms and attached to the pins F. When the bag has been filled, the arms C and C' are readily released from the bag by simply forcing the outer or free ends of the arms inwardly 85 against the tension of the spring I, when the bag may be detached from the points F and removed from the arms.

Having thus described my invention, what I claim to be new, and desire to secure by 90 Letters Patent, is—

The herein-described bag-holder, the same comprising, in combination, the frame A, the curved arm C, pivoted to the upper face of the frame upon a fixed pivot and having 95 straight portion beyond its pivot, the curved arm C', pivoted upon a rod extended through the slot H' and provided with straight por-

tion beyond its pivot, the lower end of said rod being provided with a thumb-nut H², said arms C and C' being provided at points slightly in advance of their pivotal points 5 with rearwardly-inclined pins F and at their rear ends connected by means of a spiral spring, said spring having one end passed through the straight portion of the arm C and secured thereto and the rear part of the frame 10 A being provided with downwardly-extended

lugs adapted to engage the edge of a table or other support, substantially as and for the purpose described.

In testimony whereof I affix my signature in presence of two witnesses.

JAMES H. CRAIG.
